(57) **CLAIM**

We claim the ornamental design for a removable top for a portable vaporizer, as shown and described.

DESCRIPTION

FIG. 1 is an upper right rear perspective view of a removable top for a portable vaporizer shown on a disclaimed portable vaporizer;

FIG. 2 is a top plan view of the removable top of FIG. 1; FIG. 3 is a right side elevational view of the removable top of FIG. 1, where the left side elevational view is a mirror image thereof;

FIG. 4 is a front elevational view of the removable top of FIG. 1;

FIG. 5 is a rear elevational view of the removable top of FIG. 1;

FIG. 6 is a bottom plan view of one embodiment of the removable top of FIG. 1; and,

FIG. 7 is a bottom right front perspective view of the embodiment of FIG. 6.

The broken line showing of the portable vaporizer in FIG. 1 is for the purpose of illustrating environmental structure and forms no part of the claimed design. The broken lines in FIGS. 6 and 7 define the bounds of the claimed design form no part thereof.
